James L. Hvale, Chicago, Ill., assignor to Ekco Products
Company, Chicago, Ill., a corporation of Illinois

Application February 19, 1959, Serial No. 54,675

Term of patent 14 years

(Cl. D44—1)

Fig. 1 is a perspective view of a culinary beater showing my new design;

Fig. 2 is an enlarged scale front elevational view of the handle and gear housing;

Fig. 3 is a right side elevational view thereof;

Fig. 4 is a left side elevational view thereof; and Fig. 5 is a top plan view thereof.

The essential features of my design reside in the portion shown in solid lines on the drawing.

I claim:

The ornamental design for a culinary beater, as shown and described.
